(57) **CLAIM**

I claim the ornamental design for a floor mat for tire cleaning, as shown and described.

DESCRIPTION

FIG. 1 is a perspective view of a floor mat for tire cleaning showing the new design;

FIG. 2 is a top view thereof;

FIG. 3 is a bottom side view thereof;

FIG. 4 is a right side view thereof;

FIG. 5 is a left side view thereof;

FIG. 6 is a front end view thereof; and,

FIG. 7 is a rear end view thereof.
